UNITED STATES PATENT OFFICE

JOHN F. O'CONNOR, OF CHICAGO, ILLINOIS, ASSIGNOR TO W. H. MINER, INC., OF CHICAGO,
ILLINOIS, A CORPORATION OF DELAWARE

RAILWAY DRAFT RIGGING

Application filed December 22, 1927. Serial No. 241,745.

This invention relates to improvements in railway draft riggings.

One object of the invention is to provide a draft rigging for railway cars, including shock absorbing means having a relatively longer stroke in buff than in draft, wherein the buffing shocks are absorbed by a spring shock absorbing mechanism and a combined spring and friction shock absorbing mechanism, and the shocks in draft are absorbed by the friction shock absorbing mechanism only.

Another object of the invention is to provide in a mechanism of the character indicated, having a relatively longer stroke than has been the practice heretofore, means for properly supporting the coupler to prevent tilting thereof, thus assuring proper axial alignment of the coupler shank and shock absorbing means in all positions assumed by the parts during operation.

A more specific object of the invention is to provide in a railway draft rigging, shock absorbing means having a relatively short stroke in draft and a much greater stroke in buff, actuated through the medium of the usual coupler, wherein are employed a spring shock absorbing means and a combined friction and spring shock absorbing means, and the entire shock absorbing mechanism, comprising the two different means, together with the coupler, are supported by unitary yoke means, and wherein the entire shock absorbing mechanism is operated in buff and the friction means only is actuated in draft.

Other and further objects of the invention will more clearly appear from the description and claims hereinafter following.

In the drawing, forming a part of this specification, Figure 1 is a longitudinal, vertical, sectional view of a portion of a railway car showing my improvements in connection therewith, the parts being illustrated in the position assumed in full release of the shock absorbing mechanism. And Figure 2 is a horizontal, longitudinal, sectional view, cor-

responding substantially to the line 2—2 of Figure 1.

In said drawing, 10—10 indicate channel-shaped center sills of well known form. The transverse angle end sill of the car is designated by 11, and the end wall sheathing is designated by 12. The cover plate for the sills 10 is indicated by 13, and the usual buffer block 14 is secured to the angle sill 11. The buffer block supports the carry iron 15, which may be formed integral therewith or may comprise a separate detachable member. The buffer block is also secured to the end sill member, which is designated by 116. One of the body bolsters of the car is indicated by 117, and a filler casting 118, disposed between the sills 10, may either comprise a separate member or be formed integral with the body bolster 117. As shown, the filler casting or block 118 is secured to the sills 10 by rivets.

In carrying out my invention, the center sills 10 are provided with aligned slots 16—16 at the forward ends thereof, the slots being reinforced by stop castings 17—17, which have openings corresponding to the openings or slots in the sills and which may be formed as an integral part of the buffer block or may comprise separate members. As shown in the drawing, the stop castings or lugs 17 terminate short of the rear ends of the slots 16 of the center sills. The center sills are also provided with rear stop lugs 18—18 and two sets of intermediate stop lugs 19—19 and 20—20. The stop lugs or castings 18, 19, and 20, may be secured to the draft sills in any suitable manner, but are herein shown as secured thereto by rivets. The stop lugs or castings 18 are of such a length that the rear ends thereof abut the front face of the filler casting 118, so that the same will be braced thereby. As shown in the drawing, the intermediate stop castings 20 are spaced a greater distance from the front stop castings 17 than from the stop castings 19. The stop castings 19 are of

greater length than the stop castings 20, and each of the stop castings 19 and 20 provide abutment faces on the opposite ends thereof, forming the stops proper.

5 In my improved railway draft rigging, as shown, is included a standard coupler, indicated broadly by the reference character A; a yoke means B; a combined friction and spring shock absorbing mechanism C; a spring shock absorbing mechanism D; front, intermediate, and rear followers, designated respectively by E, F, and G; and a coupler key H.

15 The yoke means B is in the form of an elongated tubular housing of substantially rectangular cross-section, having longitudinally disposed spaced side walls 21—21, horizontally disposed spaced top and bottom walls 22—22, and a vertical rear end wall 23.

20 The top, bottom, and side walls of the housing B, extend forwardly and project an appreciable distance beyond the outer face of the buffer block 14. The top wall of the housing B is provided with a vertical up-25 standing flange 24 at the forward end thereof, adapted to act as an abutment means for the vertical inner face of the coupler head or horn. The normal spacing between the flange 24 and the end face of the buffer

30 block preferably corresponds to the full compression stroke of the mechanism in buff. The coupler A has the shank thereof telescoped within the housing B, with the inner side of the coupler head bearing on, or abutting directly, the flange 24. The coupler A, as disclosed, is of that type having a forwardly flaring shank, and the side walls at the forward end of the housing A are correspondingly flared outwardly, as indicated at

35 25—25, to permit of the necessary lateral movement of the coupler. The coupler A is secured to the housing B by means of the transversely disposed key H, which extends through aligned openings in the coupler

40 shank and side walls of the housing, the opposite ends of the key H working in the slots 16 of the center sills. The key H is of the headed type and is retained in assembled relation with the railway draft rigging by

45 means of the usual cotter pin or other holding means inserted through the key at the opposite end to the head. As shown in the drawing, and especially in Figure 2 thereof,

50 the key H fits the openings in the shank of the coupler A and the side walls 21 of the housing B closely, so that the coupler and housing will move in unison. It will be evident that the slots 16 of the center sills permit longitudinal movement of the key H in both directions; however, these slots are so

55 designed that the key will be held against vertical displacement with respect to the sills. The slots or openings in the shank of the coupler and the side walls of the housing are also so designed that no relative movement of the

key in a vertical direction with respect to the coupler and housing is permitted. The front end portion of the shank of the coupler A is directly supported by a transverse block or bar 32, which is secured in any suitable manner to the bottom wall 22 of the housing and engages the shank of the coupler immediately in back of the coupler head.

70 The combined friction and spring shock absorbing mechanism comprises the usual friction shell 26 having a pair of friction shoes co-operating therewith, engaged by a wedge member 27. The movement of the friction shoes is resisted by the usual spring element 28, which co-operates with a spring follower bearing on the inner ends of the shoes. As disclosed, the friction shell is of rectangular cross-section having opposed inwardly converging friction surfaces on the opposite side walls thereof. The parts of the friction shock absorbing mechanism are held assembled by the usual retainer bolt. The wedge member 27 of the friction mechanism bears directly on the rear follower G, and the closed end wall of the shell bears on the intermediate follower F.

75 The spring shock absorbing mechanism D comprises, as shown, an inner and an outer coil spring. Although two springs are shown, it is evident that the number of springs used may be varied within wide limits. The shock absorbing spring resistance D is interposed between the front follower E and the intermediate follower F, the front follower E bearing directly on the inner end of the shank of the coupler A. As clearly disclosed in Figure 2, the followers E, F, and G, are all in the form of heavy rectangular plates. The follower E extends through

80 aligned openings in the side walls 21 of the housing B and tightly fits these openings so that the follower will move in unison with the housing, both in buff and in draft. The intermediate follower F has the opposite ends thereof projecting through transversely aligned openings 30—30 in the side walls of the housing B, the openings being of such a length that a certain amount of relative movement is permitted between the housing and the follower F during a buffing or inward movement of the housing. In the normal full release position of the parts, as shown, the follower F bears directly on the inner ends of the stop castings 20 and is spaced

85 from the rear end walls of the openings 30, thereby permitting outward movement of the casing B to a limited extent in draft. The rear follower G has the opposite ends thereof projecting through aligned openings 31—31 in the side walls of the housing B and co-operates with the inner ends of the stop lugs or castings 19 and the front ends of the stop lugs 18. As shown, the openings 31 are of such a dimension lengthwise of the housing B as to 90 permit a full compression stroke of the device

in buff before the front end walls of said openings will engage the rear follower G. The parts are so proportioned that the end wall 23 of the housing B will engage the front face of the filler casting 18 at the same time that the follower G is engaged by the front end walls of the openings 31. Upon reference to the drawing, it will be evident that in the normal position of the parts, as shown 5 in Figure 2, the followers E and G are spaced equally from the stop lugs or castings 17 and 19, respectively. The spacing between these parts corresponds also to the spacing between the key H and the front end walls of the slots 16 of the center sills. It will thus be evident that outward movement of the coupler A and the housing B will be arrested simultaneously 10 by the key H and the followers E and G. It will also be evident that the amount of movement permitted in draft is thus considerably less than that permitted in buff. Although the amount of movement in draft of my improved shock absorbing mechanism may be varied within wide limits, the amount of 15 movement permitted, as disclosed in the drawing, is preferably approximately two and one-half inches. The follower F is preferably spaced such a distance from the front ends of the stop castings 19 that the follower 20 will be arrested in its movement before the full compression stroke of the mechanism is reached in buff. The amount of movement allowed may be varied within wide limits, and, as shown in the drawing, the same is approximately 25 two and one-half inches. It is also pointed out that the total amount of movement of the coupler and housing B in buff, may also be varied within wide limits, as long as the same is greater in extent than 30 the movement in draft. As shown in the drawing, the total movement in buff is preferably substantially five inches, there being two and one-half inches of movement permitted between the housing and the follower 35 F to effect compression of the spring resistance D, and two and one-half inches of movement between the followers F and G to provide the frictional resistance.

The elongated housing B is supported adjacent the casting 18 by a saddle plate 33, and is further supported intermediate this saddle plate and the carry iron 15 by another saddle plate 34. The saddle plates 33 and 34 are fixed to the draft sills by any suitable means, the same being herein shown as secured by 40 bolts, thereby making the saddle plates readily detachable.

The operation of the shock absorbing mechanism of my improved railway draft rigging 45 is as follows, assuming an inward or buffing movement being applied to the coupler A; the housing B will be moved inwardly in unison with the coupler A through the medium of the connecting coupler key H, and by the follower E which is engaged directly by the butt

end of the coupler shank, the rearward movement of the follower E compressing the spring resistance D against the follower F, which, at the beginning of the compression stroke, will be held substantially stationary 50 by the friction shock absorbing mechanism, inasmuch as the resistance of the latter is appreciably greater than that of the spring shock absorbing mechanism D. During the further rearward movement of the parts, when the compression of the spring D becomes sufficiently great to balance or exceed the resistance offered by the friction shock absorbing mechanism C, the follower F will be moved rearwardly, thereby forcing the friction shell of the friction shock absorbing mechanism rearwardly also, and moving the same relatively to the friction shoes which are held against movement by engagement with the wedge block 27 which bears on the rear follower G, which, in turn, is held against movement by the stop lugs 18. The compression of the mechanism will continue either until the actuating force is reduced or movement of the housing B is positively limited by 55 engagement with the filler casting 18 and by engagement of the front follower E with the front ends of the stop castings 20, engagement of the key H with the inner end walls of the slots 16 of the center sills, engagement of the front end walls of the openings 30 with the follower F, and engagement of the follower F with the front ends of the stop castings 19, and engagement of the front 60 end walls of the openings 31 with the rear follower G. During release, upon the actuating force being reduced, the springs of the spring resistance mechanism and the friction shock absorbing mechanism will restore all of the parts to normal position, outward movement of the housing B being limited by the follower G movement of which in turn is prevented by the friction shock absorbing mechanism which bears on the intermediate follower F, 65 the latter being held against forward movement by the stop castings 20.

Upon a draft or pulling action being applied to the coupler A, the housing B will be pulled outwardly in unison with the coupler through the medium of the connecting key H, thereby pulling the rear follower G forwardly and compressing the friction shock absorbing means between the follower G and the follower F, the latter being held against outward movement by the stop lugs or castings 20, as hereinbefore pointed out. Forward or outward movement of the parts will be limited by the key H engaging the front end walls of the slots 16, the follower E engaging the stop lugs 17, the inner end walls of the openings 30 engaging the follower F which is held by the stop lugs 20, and the follower G engaging the rear ends of the stop lugs or castings 19. Upon release of 70 75 80 85 90 95 100 105 110 115 120 125 130

the mechanism, the parts will be restored to their normal position after a draft action, by the expansion of the spring resistance of the friction shock absorbing mechanism C, 5 which forces the friction shoes and wedge block 27 outwardly, carrying the rear follower G therewith, and thus pulling the housing rearwardly also.

While I have herein shown and described 10 what I consider the preferred manner of carrying out the invention, the same is merely illustrative, and I contemplate all changes and modifications which come within the scope of the claims appended hereto.

15 I claim:

1. In a draft rigging for railway cars having spaced center sills and a carry iron adjacent the outer ends of the sills, the combination with shock absorbing means disposed between the sills, said shock absorbing means including a friction shock absorbing mechanism comprising a friction shell, a friction system co-operating therewith, and spring means resisting relative movement 20 of the friction system and shell, and an independently acting spring resistance; of a coupler; yoke means within which the coupler shank is loosely fitted so as to have lateral swinging movement connecting the coupler 25 operatively with said shock absorbing means, the inner end of said yoke means enclosing said shock absorbing means and supporting the same, said yoke means being supported at the outer end by said carry iron; means 30 co-operating with said shock absorbing means and yoke means for actuating said friction shock absorbing mechanism and spring resistance upon a buffing action being applied to the coupler, and for actuating said 35 friction shock absorbing mechanism only upon a draft action being applied to the coupler; a member for anchoring the coupler to the yoke for movement in unison both in buff and draft, said member co-operating 40 with means on the sills for preventing vertical movement of said member, but permitting limited longitudinal movement thereof with respect to the sills; and means outwardly of the carry iron on the yoke means for supporting the coupler shank.

2. In a draft rigging for railway cars having spaced center sills, the combination with a friction shock absorbing mechanism disposed between said sills; of a spring shock absorbing mechanism disposed between said sills; a coupler; unitary yoke means for housing said friction and spring shock absorbing mechanisms; means for connecting the coupler and yoke for movement in unison; follower means interposed between said friction and spring shock absorbing means for actuating the friction shock absorbing mechanism through the spring shock absorbing mechanism in buff; means on the sills for holding said follower means against outward

movement in draft to prevent compression of said spring shock absorbing mechanism and act as outer abutment means for said friction shock absorbing mechanism; a front follower interposed between the spring shock absorbing mechanism and the coupler shank, said follower being movable in unison with the yoke in both buff and draft; stop means on the sills for limiting the inward and outward movement of said last named follower; 70 a rear follower co-operating with the friction shock absorbing mechanism; stop means on the sills for limiting inward and outward movement of said rear follower; and abutment means on the yoke for actuating the rear follower in draft only.

3. In a draft rigging for railway cars having spaced center sills, the combination with yoke means disposed between said sills; of a coupler connected to said yoke means for movement in unison therewith in both buff and draft; front, intermediate, and rear followers co-operating with the yoke, said front follower being movable in unison with the yoke in both buff and draft, said rear follower being movable in unison with the yoke in draft only; stop means on the sills for limiting the inward and outward movement of each of said followers; and shock absorbing means disposed between said front and intermediate followers, and additional shock absorbing means interposed between said rear and intermediate followers, said last named shock absorbing means being of greater capacity than said first named shock absorbing means, whereby the latter will be compressed to a predetermined extent in buff before compression of the other shock absorbing means.

4. In a railway draft rigging including draft sills provided with front, rear and intermediate stop shoulders, the combination with a tubular yoke member, said yoke member receiving the buffing and draft shocks; of front, intermediate and rear followers co-operating with said yoke member, said front follower being fixed with respect to the yoke, said intermediate follower extending through elongated openings in the side walls of the yoke and held against outward movement by said intermediate stop shoulders, and said rear follower engaging the rear end wall of the yoke and extending through openings in the side walls thereof to permit relative movement of the yoke and rear follower during a buffing action, said rear follower being held against rearward movement by said rear stop shoulders; shock absorbing means interposed between said front and intermediate followers; and friction shock absorbing mechanism interposed between said intermediate and rear followers, said friction shock absorbing mechanism including a friction shell member, a friction system cooperating therewith and spring means within the shell member, said

system having its movement resisted by said spring means, said system also including a wedge member, one of said members of the friction shock absorbing mechanism bearing on the intermediate follower and the other of said members of the friction shock absorbing mechanism bearing on the rear follower.

5. In a railway draft rigging, the combination with draft sills provided with front, intermediate and rear stop-acting means, respectively; of a front follower, an intermediate follower, and a rear follower, the front follower being normally spaced from its corresponding stop-acting means and the other two followers in engagement with their respective stop-acting means; cushioning devices, one between the rear and intermediate followers and the other between the intermediate and front followers; and yoke-acting means, said yoke-acting means and front follower having constant shouldered engagement, the yoke-acting means and the rear follower having shouldered engagement during draft movement, only, and the yoke-acting means being movable relative to the intermediate follower in both buff and draft and adapted to have shouldered engagement with the intermediate follower in buff after a partial buff stroke, to thereby actuate the intermediate follower in buff during the latter part of the buff stroke.

6. In a railway draft rigging, the combination with inner and outer stop shoulders; of a coupler; yoke-acting means connected to the coupler for movement therewith in both buff and draft; a front follower movable in unison with the yoke in both buff and draft; a rear follower movable with the yoke in draft and held against movement during buff; an intermediate follower, said intermediate follower being movable with respect to the yoke in both buff and draft; shock absorbing means interposed between the front and intermediate followers and an additional shock absorbing means interposed between intermediate and the rear followers; a stop shoulder for holding said intermediate follower against movement during draft, thereby producing compression of the second named shock absorbing means only; and means for limiting movement of the intermediate follower in buff to less than the full buffing stroke of the mechanism.

7. A yoke member for railway draft riggings, said yoke member being of tubular form and open at one end, said open end being adapted to receive the shank of a coupler, said yoke member having aligned key receiving slots in the side walls thereof, the bottom wall of said yoke extending forwardly of the slots and forming a support for the coupler shank outwardly of said slots, said yoke having aligned openings in the side walls thereof rearwardly of said slots adapted to accommodate and fit a front follower member, said

yoke having at the rear end aligned elongated openings in the side walls thereof adapted to movably accommodate a rear follower, and said yoke also having aligned elongated openings in the side walls thereof between said openings for the front and rear followers adapted to movably accommodate an intermediate follower.

In witness that I claim the foregoing I have hereunto subscribed my name this 20th day 75 of December, 1927.

JOHN F. O'CONNOR.
